UNITED STATES PATENT OFFICE.

GEOEGE LANE, OF POUGHKEEPSIE, NEW YORK, ASSIGNEE TO LANE BROTHERS COMPANY, A CORPORATION OF NEW YORK.

LIFTING-JACK.

1,122,235.

Specification of Letters Patent. Patented Dec. 22, 1914.

Application filed May 8, 1914. Serial No. 887,278.

To all whom it may concern:

Be it known that I, GEORGE LANE, citizen of the United States, residing at Poughkeepsie, New York, have invented certain new and useful Improvements in Lifting-Jacks, of which the following is a specification.

My present invention relates to improvements in lifting jacks of the type known as step down jacks, and has among its objects to provide a device of this character capable of economic production, of extreme lightness combined with the requisite strength, and embodying raising and lowering mechanism free from loose screws, nuts or bolts, and of extreme simplicity, thus reducing liability of derangement and facilitating repairs or adjustment by the ordinary mechanic.

The invention includes the novel features of construction and arrangement and combination of parts hereinafter described and particularly defined by the appended claims.

A jack constructed in accordance with my invention is illustrated in the accompanying drawings, in which—

Figure 1 is a side elevation, partly broken away. Fig. 2 is a view at right angles to Fig. 1 looking toward the right. Fig. 3 is a sectional elevation of the upper portion of the jack. Fig. 4 is a section on line 4—4 of Fig. 3, and Fig. 5 is a section on line 5—5 of Fig. 3.

Referring by reference characters to this drawing, the numeral 1 designates the base which is preferably composed of a square plate of sheet steel of desired size and thickness, and 2 a standard within which is guided the lifting bar 3. This standard is of special form designed to secure combined lightness and strength, and comprises a pair of channel irons 2^a and 2^b of steel or other suitable material of different depths and fitting one within the other, as shown, so as to leave a space between the bases of the channel irons and the side walls of the channel iron 2^a which receives and guides the lifting bar. The edges of the channel irons are securely riveted together, as indicated at a, and the outer channel 2^a is provided at its lower end with outwardly turned integral wings or flanges 2^c which are firmly secured to the base by suitable means such as rivets, as indicated at c. The lifting bar 3 is pro-

vided on one face with the usual ratchet teeth 3^a, and at its upper end with a suitable head 3^b.

For a suitable distance adjacent the upper end of the standard the inner channel iron 2^b is cut away or omitted to permit the holding and lifting pawls to cooperate with the ratchet teeth of the lifting bar. The holding pawl 4 is pivotally mounted upon a pin 4^a passing through suitable openings in the edges of the channel irons, while the lifting pawl 5 is pivotally connected to the end of the lifting lever 6, preferably by bifurcating the end of the pawl and reducing the end of the lifting lever to permit it to fit between the legs of the pawl and be connected thereto by the pivot pin 7.

The lifting lever is pivoted between the side plates 8 which, with the cover or cap 9, constitute a casing to receive the pawl controlling parts, these side plates 8 being riveted or otherwise secured to the edges or side walls of the channel iron 2^a. The lifting lever is pivotally mounted upon a pin 10 supported by the side plates, and the extensions or collars 8^a are provided on each side of the lifting lever for keeping it properly centered on the pin. By making these extensions or collars integral with the lifting lever, the latter is held properly centered and a longer bearing surface on the pivot pin afforded.

The lifting and holding pawls are normally spring-pressed toward the lifting or ratchet bar, and act alternately in the manner well understood by those skilled in the art. In order that the pawls may be operated automatically to lower the lifting bar step by step, I provide pawl controlling mechanism which will now be described.

To one of the side plates 8 are pivoted upper and lower bell crank levers 11 and 12, the pivots 11^a and 12^a being located respectively above and below a horizontal line passing through the pivot of the operating lever 6. These bell crank levers are adapted to be pushed toward the pawl by suitable spring mechanism preferably in the form of a spring interacting between the two pawls, such for instance as the spring C, and when so pressed toward the pawls these bell crank levers in their turn press against the pawl with a yielding pressure, permitting these to

alternately ride over the teeth of the lifting bar when the jack is operated for lifting purposes as hereinbefore referred to. Any form of pushing connection may be used to 5 transmit the elastic tension of the spring C through the pawls. In order that the pawls may be operated to effect the step by step lowering in the manner hereinafter described, it is necessary that there should be 10 an elastic connection between the bell cranks 11 and 12 and the pawls 5 and 4 through which said bell crank levers will, when rocked on their pivots, tend to yieldingly pull on the pawls 5 and 4. I find that I can 15 accomplish this double function of pushing on the pawls in one direction and yielding or elastic pull on them in the opposite direction by means of close coil springs 13 and 14 connected respectively to lugs or eyes on the 20 pawls, and similar eyes on the ends of the bell crank levers. When the bell crank levers are free to move toward the pawls under the action of the spring C, the coils of the spring 13 and 14 being in contact, said 25 springs act practically as rigid links, thus pushing the pawls toward the ratchet teeth, any yielding permitted to the pawls being due to the action of the spring C. It will be apparent, however, that either of the bell 30 crank levers 11 or 12 being swung away from the pawls 5 or 4, this would place a tension on the respective spring 13 or 14. In order to effect this movement of the bell crank levers to pull the pawls out of engagement 35 with the ratchet teeth at the proper time to permit the lowering of the jack as the handle is moved up and down, I provide means on the handle adapted to coöperate with the arms or portions 11^b and 12^b of the bell 40 crank levers, this means on the handle or operating lever being movable so that it can be set in a position ineffective with relation to the bell crank lever during the lifting operation, and being shifted to effective 45 position for the step by step lowering. A convenient means of effecting this purpose is to provide a rotary contact member 15 thin and relatively wide, and of such dimensions that when it is turned in horizontal 50 position it will move up and down with the lifting lever without either of its flat sides coming in contact with the bell crank levers. When turned into a vertical position as shown in Fig. 3 however, as the lifting lever 55 is moved up and down, the upper and lower edges of the contact piece will alternately contact with the arms or portions 11^b and 12^b of the bell crank levers, rocking them on their pivots and alternately placing tension on springs 13 and 14.

It is thought that the operation of the parts thus described in the step by step lowering of the lifting bar will be apparent, but it may be briefly stated as follows: 60 With the contact piece turned vertically,

when the handle or lifting lever is lowered, the lower bell crank 12 is forced backwardly, stretching the spring 14, and when the load is taken by the top pawl 5 the lower, or holding pawl 4 is pulled by the spring 13 out of engagement with the ratchet teeth. Then on raising the handle lever 6 (which lowers the load) the contact piece releases the lower bell crank lever, which again takes up its normal position actuated by the spring C to push the pawl forward, and when the lifting pawl has been sufficiently lowered the holding pawl intercepts the next tooth and holds the bar 3 against further downward movement. In the meantime, 65 the upward movement of the contact piece 15 has rocked the bell crank 11, applying the tension to spring 13, so that the moment the weight of the load is taken by the holding pawl and the upper pawl relieved of the 70 weight, the spring 13 immediately pulls the upper or lifting pawl out of engagement with the ratchet teeth. In either case the bell crank lever can not get back into its normal position until the lifting lever has 75 approached the center, that is, until there has been sufficient movement for the pawl to pass the point of the corresponding tooth in the rack.

A convenient manner of effecting the 80 rocking of the contact piece or control device is to provide it with a thumb or control lever 16. The end of this control pin has a surface squared as indicated at 15^a that projects outside the operating lever on 85 the opposite side and against which a spring 17 presses, tending to hold it in either the raising or lowering rotative position as placed. Outside of this the control lever is 90 attached. A feature of this spring arrangement is that the control device will be thrown fully into position and held there, for as soon as it well passes center the 95 spring aids in the movement. This avoids the objections incident to careless operators failing to get the control lever fully into 100 position as well as its failure to stay there.

In order that the lifting bar may be quickly lowered or released and allowed to drop when no load is on it, I provide the 105 bell crank levers with finger projections 11^x and 12^x which may be pressed toward each other to simultaneously rock both bell crank levers and place both springs 13 and 14 under tension simultaneously.

The lifting lever is provided with the 110 usual socket 6^a to receive an extension lever (not shown).

Having thus described my invention what I claim is:

1. A jack comprising a standard or guide, a lifting bar, an actuating lever, a lifting pawl and a holding pawl coöperating with said lifting bar, a spring for normally pressing said pawls into operative relation to the 115

lifiting bar, a separate spring connected to each pawl, and means on the actuating lever for alternately applying tension to said separate springs.

5 2. A jack comprising a standard or guide, a ratchet bar longitudinally movable therein, a holding pawl pivotally connected to the guide and adapted to engage the ratchet bar, an actuating lever, an operating pawl pivoted to the lever and engaging the ratchet bar, spring means for pressing said pawls normally toward the ratchet bar, and contact means on the actuating lever for alternately applying yielding tension to said 15 pawls tending to draw them outwardly from the ratchet bar as the lever is oscillated, substantially as described.

3. A jack comprising a standard or guide, a ratchet bar, an actuating lever pivotally connected with the guide, a holding pawl pivoted to the lever, a pair of bell crank levers pivotally connected with the lifting lever, a spring interacting between said bell crank 20 levers and tending to push the pawls into engagement with the ratchet bar, springs connecting the bell crank levers with the pawls, and means carried by the actuating lever for operating said bell crank levers as the 25 actuating lever is oscillated.

4. A jack comprising a standard or guide, a bar movable longitudinally thereof, a holding pawl pivotally connected with the guide and coöperating with said bar, an actuating lever, a pawl pivotally connected therewith and coöperating with said bar, a pair of bell crank levers pivotally supported 35 from the casing, close coiled springs connecting said bell crank levers with the pawls, a spring interacting between said bell crank levers, and means carried by the actuating lever for rocking said bell crank levers as the actuating lever is oscillated.

5. A jack comprising a standard or guide, a ratchet bar, an actuating lever pivotally connected with the guide, a holding pawl pivoted to the guide, an operating pawl pivoted to the actuating lever, a pair of bell 40 crank levers pivotally supported from the standard, a spring interacting between said bell crank levers and tending to push the pawls into engagement with the ratchet bar, springs connecting the bell crank levers with the pawls, a contact device carried by the actuating lever for operating said bell crank levers as the hand lever is oscillated, and means for moving said actuating device into 45 and out of operative position with relation to said bell crank levers.

6. A jack comprising a standard or guide, a lifting bar, an actuating lever, a lifting pawl and a holding pawl coöperating with said lifting bar, a pair of spring-pressed bell crank levers pivotally supported from 50 the standard and adapted to press said pawls

toward the lifting bar, springs connecting said bell crank levers with the pawls, and a contact device carried by the actuating lever and movable into and out of the path of the bell crank levers.

7. A jack comprising a standard or guide, a lifting bar, an actuating lever, a lifting pawl and a holding pawl coöperating with said lifting bar, a spring for normally pressing said pawls into operative relation to the lifting bar, a separate spring connected to each pawl, and means operated by the actuating lever for alternately applying tension to said separate spring, and means for disengaging both pawls from the lifting 70 bar to allow the same to drop.

8. A jack comprising a standard or guide, a lifting bar, an actuating lever, a lifting pawl and a holding pawl coöperating with said lifting bar, a spring for normally pressing said pawls into operative relation to the lifting bar, a separate spring connected to each pawl, and means operated by the actuating lever for alternately applying tension 85 to said separate springs, and means for rocking the bell cranks simultaneously.

9. A jack comprising a standard or guide, an actuating lever, a lifting pawl and a holding pawl coöperating with said lifting bar, a pair of bell crank levers pivotally 90 supported from the standard and adapted to press said pawls toward the lifting bar, a C shaped spring having its ends connected to said bell crank levers, elastic connections between the bell crank levers and pawls, 95 and a contact device carried by the operating lever.

10. A jack comprising a standard or guide, a lifting bar, an actuating lever, a lifting pawl and a holding pawl coöperating with said lifting bar, a pair of spring-pressed bell crank levers pivotally supported from the standard and adapted to press 100 said pawls toward the lifting bar, springs connecting said bell crank levers with the 105 pawls, and a rotary contact device carried by the actuating lever and having a contact portion adapted to contact with said bell crank levers in one position of the contact device.

11. A jack comprising a standard or guide, a lifting bar, an actuating lever, a lifting pawl and a holding pawl coöperating with said lifting bar, a pair of spring-pressed bell crank levers pivotally supported 110 from the standard and adapted to press said pawls toward the lifting bar, springs connecting said bell crank levers with the pawls, and a rotary pin carried by said actuating lever and having a thin and relatively wide portion projecting between said bell crank levers, substantially as described.

12. A jack comprising a standard or guide, a lifting bar, an actuating lever, a lifting pawl and a holding pawl coöperating 115

ing with said lifting bar, a pair of spring-pressed bell crank levers pivotally supported from the standard and adapted to press said pawls toward the lifting bar, springs connecting said bell crank levers with the pawls, and a rotary pin carried by said actuating lever and having a thin and relatively wide portion projecting between said bell crank levers, said pin also having a non-

circular portion, and a controlling spring bearing against said non-circular portion.

In testimony whereof, I affix my signature in presence of two witnesses.

GEORGE LANE.
